UNITED STATES PATENT OFFICE.

ERNEST W. CAMPBELL, OF PROVIDENCE, RHODE ISLAND, ASSIGNOR TO
WILLIAM H. MANCHESTER, OF SAME PLACE.

DESIGN FOR A HANDLE FOR SPOONS OR SIMILAR ARTICLES.

SPECIFICATION forming part of Design No. 31,223, dated July 18, 1890.

Application filed June 16, 1890. Serial No. 720,859. Term of patent 31 years.

To all whom it may concern:

Be it known that I, ERNEST W. CAMPBELL, a citizen of the United States, residing at Providence, in the county of Providence, State of Rhode Island, have invented and produced a new and original Design for the Handles of Spoons and Similar Articles, of which the following is a specification, reference being had to the accompanying drawings, forming part thereof.

Figure I is a face view of a spoon-handle, showing my design. Fig. II is a central vertical section of the same.

The leading features of my design consist of a mask ornament surmounted by a panel with marginal scroll ornamentation in conjunction with a stem faced with a series of floral pendants. The style herein disclosed represents a period of the French renaissance.

In the drawings, A represents the blade, and B the stem, of the handle. At their junction is an ornamental mask *a*, pendent from which is a series of gradually-diminishing floral or-

naments *b*, terminating in circular beads *c*. 25 On either side of the stem are single marginal beading *d d*. The panel *e* of the blade is bordered by overlying foliates variously arranged, which also serve to form the contour of the handle. The lower panel portion is 30 slightly swelled in outline by inwardly-inclined foliates *f f*, with triple terminations. Extending upwardly, the panel broadens in general outline, embraced on either side by oppositely-disposed foliated scrolls *l m*, 35 embedded in which are series of spherical beads *n n*. The crest of the panel, which is also the termination of the handle *o*, consists of a bunch of four diverging scrolls.

Having thus described my invention, what 40 I claim as new, and desire to secure by Letters Patent, is—

The design for the handle of a spoon or similar article as herein shown and described.

ERNEST W. CAMPBELL.
